UNITED STATES PATENT OFFICE.

JOHN JAY HANNAHS, OF NEW YORK, AND ANTHONY A. HIEBER, OF BROOKLYN, NEW YORK, ASSIGNEES, BY DIRECT AND MESNE ASSIGNMENTS, TO UNIVERSAL TYPEWRITER COMPANY, A CORPORATION OF NEW YORK.

INTERCHANGEABLE CARRIAGE FOR TYPE-WRITERS.

SPECIFICATION forming part of Letters Patent No. 793,069, dated June 27, 1905.

Application filed August 18, 1902. Serial No. 120,157.

To all whom it may concern:

Be it known that we, JOHN JAY HANNAHS, residing at 210 West Fourth street, New York, county of New York, and ANTHONY A. HIEBER, residing at 1243 Putnam avenue, Brooklyn, county of Kings, State of New York, citizens of the United States, have invented certain new and useful Improvements in Interchangeable Carriages for Type-Writers, fully described and represented in the following specification and the accompanying drawings, forming a part of the same.

The object of the present invention is to furnish a type-writing apparatus adapted not only to write upon an ordinary rotary platen, but also to write upon the leaves of books or other sheets of paper held upon a stationary flat platen. This object is accomplished by providing two beds, one having a flat platen adapted to hold the paper stationary and to support the type mechanism movably and the other adapted to support the paper movably and to hold the type mechanism stationary, and also providing a type mechanism having a base-frame which is fitted interchangeably to similar supports upon the two beds, so that it may be used interchangeably with either. Where the bed has a stationary flat platen, it is suited to support the leaf of a book as in other book type-writing machines, and it may also be used for writing upon flat sheets of paper larger than those which can be conveniently held by a rotary platen, and the letter-spacing is secured by the bodily movements of the type mechanism, while the line-spacing is effected by a carriage supporting the same. When the type mechanism is fitted to such bed, the paper is held stationary, as in similar type-writing machines, and the type mechanism moves beneath the fingers of the operator, and the position of the hands must be constantly changed to operate upon the moving keys; but the interchangeability of the type mechanism with the other bed and its platen enables the type mechanism to be held stationary when not writing in books and

avoids such a requirement of the operator. Upon the other bed the type mechanism is held stationary over a movable carriage, and the movement of the keys is avoided, and the movable carriage, with its rotary feeding device, furnishes the means of moving the paper for line and letter spacing under the type mechanism. The type mechanism may be of any well-known or suitable character, and the means of holding it interchangeably upon the two beds may be varied at pleasure, as the essential feature of the invention is a type-writing mechanism having one platen adapted to hold the paper stationary and having supports to hold the type mechanism movably, while the other bed has a platen adapted to hold the paper movably and has supports to hold the type mechanism stationary.

In the drawings illustrating the invention a type mechanism is shown of the class claimed in our application, Serial No. 45,810, filed February 4, 1901, in which the type-bars are arranged to strike downwardly through an open-bottom frame; but the type-bars and the means for operating them are omitted in the drawings, as they form no part of the present invention and would obscure the representation of the parts which are essential.

Figure 1 is a plan of a bed having a paper-supporting carriage and platen movable upon tracks in the lower part and having above such carriage elevated supports to receive the base-frame of the type mechanism and hold it stationary. Fig. 2 is a front view of the same; Fig. 3, a rear view of the same; and Fig. 4, a front elevation of the paper-carriage and platen, upon a larger scale, detached from the bed. Fig. 5 is a cross-section of the same, the section being adjacent to the letters A i i at the left-hand end of Fig. 1, with one of the boxes for the hinge-rail broken off to expose the guide-rolls which embrace such rail, and such box is shown separately in Fig. 6. Fig. 7 is an edge view of the bed combined with a stationary platen for use in a book type-writer, the base-frame of the type mechan-

ism being shown thereon; and Fig. 8 shows an end view of such base-frame detached from both of the beds. Fig. 8^a shows the inner side of one of the boxes for the hinge-rail 5 with the collar d' having the tooth v . Fig. 9 is a plan of the bed shown in Fig. 7, with a longitudinally - movable carriage having a guide-rail and a track-rail thereon, with the base-frame of the type mechanism fitted there- 10 to. Figs. 10 to 12 show an alternative construction.

a designates the base-frame of the type mechanism, having at the rear edge two posts b , Fig. 2, carrying grooved guide-rolls c , 15 which are fitted to a cylindrical rail d , which serves as a hinge-rail for turning the type mechanism upwardly to inspect the printing. In Fig. 5 dotted lines are extended upwardly from the base-frame a to indicate the arrangement of the type-bars t , the keys t' , and the space-bar t^2 . To permit such upturning of the type mechanism, the hinge-rail may be held stationary and the grooved faces of the rolls slipped thereon or the rolls may be 20 gripped firmly upon the hinge-rail and the ends of such rail journaled to turn as an axle. The latter construction is shown in the drawings, in which Figs. 1 to 5 show the base-frame of the type mechanism held stationary upon 25 a bed having side bars A and cross-bars B. The upper parts of the bars A are provided with lugs a' , which support the base-frame, and track-rails i are affixed to the lower part of the side bars A to support rollers h upon 30 a paper-carriage g , which carries a rotary platen g' movably beneath the type mechanism. The rear side of the carriage g is provided at opposite ends with boxes e to support the hinge-rail d . The rail is formed, as 35 shown in Fig. 1, with collars d' near each end to fit inside the boxes and prevent longitudinal movement; but the rail is detachable from the boxes, so that it may be removed from the bed, with the type mechanism, for 40 use upon another bed, as described above. The hinge-rail is provided with teeth j to serve as a rack-bar, and the usual feed-pinion k and escapement-wheel l are shown in Fig. 1, supported upon the base-frame a , so that 45 when actuated in the usual manner by the keys of the type mechanism they cause the hinge-rail and the paper-carriage g (to which it is attached by the boxes e) to move step by step beneath the type mechanism for letter- 50 spacing. The usual spring-drum m is shown in Fig. 1 attached to the bed A and connected by band n with the end of the carriage g , so as to move it in the usual manner at each actuation of the spacing mechanism. The 55 spring-drum is not shown in Fig. 5 for want of room upon the drawing, but is fully shown in Fig. 1. The carriage g is shown in Fig. 1 with guide-rolls o at opposite sides of the rotary platen g' and in Fig. 5 with small rolls 60 o' , pressed upon the tops of the guide-rolls by

springs o^2 . A knob p is connected with the guide-rolls o by gears p' , and the paper is fed across the surface of the platen step by step for line-spacing by turning the knob after writing each line. The side bars A of the 70 bed are shown formed in Figs. 2, 3, and 5 with longitudinal slots A' , through which a sheet of paper P can be inserted between the rolls o and o' and shifted intermittently for line-spacing, while the letter-spacing in the 75 lines is effected by the usual movement of the carriage beneath the type mechanism upon the rails i . The base-frame a is shown provided upon the front edge with track-rolls q for use with a stationary carriage, and such 80 rolls are utilized with the bed shown in Fig. 5 to hold the type mechanism stationary by their engagement with notches q' in the side bar A, as shown in Figs. 2 and 5. With the type mechanism held stationary the hinge-rail d , which is attached to the carriage, moves longitudinally between the guide-rolls c when fed for letter-spacing; but such hinge-rail is 85 so supported by the carriage g that the base-frame a and the type mechanism supported 90 thereby may be turned around the axis of the rail d whenever desired to inspect the printing upon the paper beneath. During this operation the track-rolls q upon the base-frame are lifted from the notches q' in the side bar 95 A and are afterward replaced in such notches, which restores the type mechanism exactly to its former relation with the paper.

The apparatus thus far described holds the type mechanism stationary, so that the keys 100 always retain the same positions under the fingers of the operator.

Figs. 7 and 9 show the base-frame of the type mechanism transferred to a line-spacing carriage having sides r' and ends r , fitted to 105 a bed which is formed with sides s and end s' , adapted to rest upon a flat rectangular platen s^2 , to clamp thereon the leaf of a book or sheet of paper s^3 , which is to be inscribed. Such a sheet is shown in Fig. 9 with a few words 110 written thereon beneath the center of the base-frame a . The rear corners of the spacing-carriage r are provided with boxes e , the same as those upon the paper-carriage g (shown in the preceding figures) and arranged 115 at the same distance apart as those upon the paper-carriage g , so that the same or a similar hinge-rail d may be fitted thereto and support the rear edge of the base-frame a while its front edge is supported by the track-rolls 120 q , resting upon the front edge r' of the spacing-carriage, as shown in Figs. 7 and 9. A spring-drum m is shown upon one end of the spacing-carriage, and a hook n' is shown upon the base-frame to engage the band n extended therefrom, so that the base-frame may be 125 moved over the paper upon the platen s^2 for letter-spacing when the escapement-wheel l is operated by the keys. The right side s of the bed is shown provided with teeth, and a pin- 130

ion n is shown journaled upon the spacing-carriage r and fitted thereto, which pinion would be actuated in the usual manner to shift the carriage upon the bed at suitable intervals for line-spacing. With this construction the line-spacing is effected by the movement of the spacing-carriage r , and the letter-spacing is effected by the movement of the type mechanism upon such spacing-carriage, 5 the base-frame a of the type mechanism being supported by the rails r' and d , with the latter of which it may be turned up, as described above, to inspect the writing when desired.

15 The hinge-rail d is turned with the type mechanism by the engagement of the rack-bar j with notches k' (see Figs. 5 and 8) in the posts b , which carry the guide-rolls c , and the type mechanism may thus be held in an 20 operative position or raised to inspect the printing by stops applied to the hinge-rail d , and such a stop is shown in Fig. 8^a for supporting the carriage to make any desired correction in the printing. When the carriage 25 is turned upward to a position of equilibrium above the hinge-rail d , it is held in such position while inspecting the printing by a tooth v upon one of the collars d' , which are rigidly fixed upon the shaft or hinge-rod d . The tooth 30 v in such position engages a pin v' upon one of the boxes e . (See Fig. 8^a.) The construction of the boxes e is immaterial, as their essential function is that of a support for the 35 guide-rail d . If a single hinge-rail be used in permanent connection with the guide-rolls c , such rail must be connected detachably with the supports upon the two beds, so as to fit interchangeably upon both; but it is immaterial whether a single hinge-rail be used 40 or corresponding guide-rails be provided upon the two beds and the guide-rolls c constructed to embrace them detachably.

In Figs. 1 to 9, inclusive, the hinge-rail d is shown removable from the boxes e , each of 45 the boxes having, as shown in Figs. 6 and 7, a hinged cap e' , pivoted upon the bearing e and provided with a latch e'' to lock it when secured over the bearing. When unlatched, such removable cap may be thrown back- 50 wardly and the hinge-rail lifted from the bearing. If a single guide-rail be used in permanent connection with the guide-rolls c , as shown in Figs. 1 to 9, the hinge-rail must necessarily be connected in a detachable manner with the supports upon the two beds, so 55 as to fit interchangeably upon both; but it is immaterial whether a single hinge-rail be used or corresponding guide-rails be provided upon the two beds and the guide-rolls c constructed to embrace them detachably. Figs. 60 10 to 12, inclusive, show the latter construction, in which the guide-rolls c are separable, so that they may be detached from the hinge-rail and the type mechanism thus be used

with either the stationary or the movable sheet of paper.

Fig. 10 shows in plan a bed A^2 , adapted to serve the same purpose as the stationary bed A B shown in Fig. 1, but having no front support for the base-frame a of the type mechanism, as the latter is designed to rest upon the moving carriage g . The bed A^2 has rails i to support the moving carriage. Posts 1 are shown projected upwardly from the rear edge of the base-frame a and the upper guide-roll c pivoted thereon, while the lower guide-roll is pivoted upon a stud 2 upon a block 3, which is movable vertically in a slot 4 in the base of the post. Levers 5 are hinged upon the posts 1 over the blocks 3, and each is 80 formed in its lower end with an eccentric slot 6, fitted to the stud 2 in one of the boxes. The levers 5 are connected by a link 7, and one of them is provided with a handle by which both can be shifted at pleasure, the eccentric slots operating to raise and lower the blocks and the lower guide-rolls c when the levers are moved back and forth. When the 85 rolls c are separated by a suitable movement of the levers, as shown in Fig. 12, the base-frame and the type mechanism attached thereto can be removed from the hinge-rail d of one bed and transferred to the hinge-rail of another bed and the rolls engaged with such latter hinge-rail by reversing the position of 90 the levers 5 to press the rolls together, as shown in Fig. 11.

Figs. 10 and 11 show ears 8 attached to the hinge-rail d in suitable positions to admit the upper guide-rolls c and to hold such rolls 100 from longitudinal movement upon the rail. The ears 8 serve to hold the type mechanism stationary over the longitudinal moving carriage g (which is shown in Fig. 12, but omitted from Figs. 10 and 11) the same as 105 the engagement of the rolls g with the notches q' , shown in the side bar A in Figs. 2 and 5.

As stated above, no side bars like A are provided with the bed shown in Figs. 10 to 12, inclusive, as the base-frame a is supported 110 wholly by the hinge-rail d and the moving carriage g .

With the construction shown in Figs. 1 to 9 the type mechanism may be used with the movable platen or the stationary platen, by 115 opening the boxes e and removing the type mechanism, with the hinge-rail d , from the supports which are connected with one of the platens, and fitting it to the supports connected with the other platen. With the construction shown in Figs. 10 to 12, inclusive, the hinge-rails are secured permanently in their supports, and the type mechanism is transferred from one platen to the other when required by separating the rolls c , as described, 120 and detaching them from the hinge-rail of one bed and transferring them to the hinge-rail of the other bed. The apparatus is thus adapted 125

to write either in stationary books or upon sheets of paper fed movably beneath the type.

From the above description, it will be seen that the invention embraces a type-writing apparatus which comprises a platen adapted to hold the paper stationary and having supports to hold the mechanism movably, and also a platen adapted to hold the paper movably with supports to hold the type mechanism stationary, and the type mechanism having means to engage the said supports interchangeably.

The particular form of the parts is not essential in the present invention, and we do not, therefore, limit ourselves to the particular mechanism shown and described herein.

Having thus set forth the nature of the invention, what is claimed herein is—

1. A type-writing apparatus having two platens provided respectively with means for holding the paper stationary, and with a carriage to hold the paper movably, and having respectively supports to hold the type mechanism movably and stationary, and type mechanism having means to engage the said supports interchangeably, whereby the said type mechanism may be used with either of the said paper-holding platens; a hinge being provided for enabling the type mechanism to swing up and off from the stationary platen.

2. A type-writing apparatus having two beds provided, the one with a platen adapted to hold the paper stationary and supports to hold the type mechanism movably, and the other, with supports to hold the type mechanism stationary and having a carriage with platen to hold the paper movably, and type mechanism adapted to operate with either of said platens and to engage the said supports interchangeably, whereby the said type mechanism may be used with either of the beds; a hinge being provided for enabling the type mechanism to swing up and off from the stationary platen.

3. A type-writing apparatus comprising a bed having a platen adapted to hold the paper stationary and supports to hold the type mechanism movably, a bed adapted to hold the type mechanism stationary and having a carriage with platen to hold the paper movably, corresponding hinge-supports connected to the respective beds, and a type mechanism having a hinge-rod to engage such supports interchangeably, whereby the type mechanism may be used upon either of the beds.

4. A type-writing apparatus comprising a bed having a platen adapted to hold the paper stationary and supports to hold the type mechanism movably, a bed adapted to hold the type mechanism stationary and having a carriage with platen to hold the paper movably, a hinge-rail, corresponding hinge-rail supports held stationary upon the respective beds, and a type mechanism with integral base-frame fitted to

such rail, the base-frame being movable upon the rail and bed where the paper is held stationary, and locked upon the rail where the paper and its carriage are movable whereby the type mechanism may be used interchangeably with either of the beds.

5. A type-writing apparatus comprising a bed having a platen adapted to hold the paper stationary and supports to hold the type mechanism movably, a bed with supports adapted to hold the type mechanism stationary, and having a carriage with a platen to hold the paper movably, a hinge-rail, corresponding hinge-rail supports being connected to the respective beds, and a type mechanism with integral base-frame fitted to such rail, the base-frame being movable upon the rail and bed where the paper is held stationary, and locked upon the bed where the paper and its carriage are movable, whereby the type mechanism may be used interchangeably with either of them.

6. A type-writing apparatus comprising a bed having a platen adapted to hold the paper stationary and supports to hold the type mechanism movably, a bed with supports adapted to hold the type mechanism stationary and having a carriage with platen to hold the paper movably, a hinge-rail, corresponding hinge-rail supports being connected to the respective beds, and a type mechanism with integral base-frame fitted to such rail, and provided with rack connection to the rail for letter-spacing, the base-frame being movable upon the rail and bed where the paper is held stationary, and locked upon the bed where the paper and its carriage are movable, whereby the type mechanism may be used interchangeably with either of the beds.

7. A type-writing apparatus comprising a bed adapted to hold the paper stationary and supports to hold the type mechanism movably, a bed with supports adapted to hold the type mechanism stationary and having a carriage with platen to hold the paper movably, a hinge-rail, corresponding hinge-rail supports being connected to the respective beds, and a type mechanism with integral base-frame having guide-rolls fitted to the hinge-rail, whereby the type mechanism may be used interchangeably with either of the beds and may be turned around upon the axis of the rail to inspect the writing beneath the base-frame.

8. A type-writing apparatus comprising a bed having a stationary platen and line-spacing carriage with a hinge-rail having type mechanism with integral base-frame fitted movably to such hinge-rail by guide-rolls, and a bed having a longitudinally-movable paper-carriage provided with means adapted to fit the hinge-rail of said base-frame, whereby the type mechanism may be used interchangeably with either of such beds.

9. A type-writing apparatus comprising a

- bed having a stationary platen and line-spacing carriage with boxes at opposite ends to hold a rail removably, and a bed having a longitudinally-movable paper-carriage with corresponding boxes at opposite ends, a hinge-rail fitted interchangeably to the boxes upon the said carriages, and a type mechanism having integral base-frame with guide-rolls to engage the said rail, whereby the type mechanism with the rail may be fitted to either of the carriages to operate interchangeably therewith.
10. A type-writing apparatus comprising a bed having a stationary platen and line-spacing carriage with boxes at opposite ends to hold a rail removably, and a bed having a longitudinally-movable paper-carriage with corresponding boxes at opposite ends, a cylindrical rail fitted interchangeably to the boxes upon the said carriages, and a type mechanism having integral base-frame with wheels to engage the said rail, and a rack and gears for letter-spacing connecting the type mechanism with the said rail, whereby the type mechanism with the rail may be fitted to either of the carriages to operate interchangeably therewith.
15. A type-writing apparatus comprising a bed having a stationary platen and line-spacing carriage with a hinge-rail and a type mechanism fitted movably to such rail by guide-rolls, and a bed having supports for the said type mechanism with means to lock the type mechanism thereon, and a carriage fitted movably to such bed beneath such type mechanism and having supports for said hinge-rail, whereby the type mechanism may be used interchangeably with either of such beds.
20. 12. In a type-writing apparatus comprising a bed having a stationary platen and line-spacing carriage with a hinge-rail and a type mechanism having guide-rolls to engage such rail, and a bed having elevated supports for said type mechanism and means to lock the type mechanism thereon, a track on the bed below such elevated supports with a carriage and platen movable thereon beneath such type mechanism, the carriage having arms to engage said hinge-rail, and a rack and gear for letter-spacing connecting the type mechanism interchangeably with the rails upon the two beds.
25. 13. In a type-writer, a type mechanism having an integral base-frame provided with opposed guide-rolls, a hinge-rail embraced by the said guide-rolls, with a rack connection to the rail for letter-spacing, and a bed having boxes to clamp the ends of such hinge-rail detachably, whereby the type mechanism may be removed from the bed with such rail for use upon other beds.
30. 14. A type-writing apparatus comprising an integral base-frame provided upon one edge with opposed guide-rolls and upon the opposite edge with track-rolls, a hinge-rail embraced by the said guide-rolls, with a rack connection to the rail for letter-spacing, a bed having boxes to clamp the ends of such hinge-rail detachably, and a track-rail to support the said track-rolls, with a flat platen beneath such rails to hold the paper stationary, and a bed adapted to hold the base-frame stationary and provided with a movable carriage having paper-supporting platen, and boxes to clamp the ends of such hinge-bar rail detachably, whereby the type mechanism may be used interchangeably with the stationary or movable platen.
35. 15. A type-writing apparatus comprising a bed having a stationary platen and line-spacing carriage with a hinge-rail having a type mechanism with an integral base-frame fitted movably to such hinge-rail by guide-rolls, and a bed having a longitudinally-movable paper-carriage thereon, said bed being provided with means, whereby the type mechanism may be used interchangeably with either of such beds.
40. 16. A type-writing apparatus comprising a bed having a stationary platen and line-spacing carriage with boxes at opposite ends to hold a rail removably, a bed having a longitudinally-movable paper-carriage with corresponding boxes at opposite ends, a hinge-rail fitted interchangeably to the boxes upon the said carriages, and a type mechanism having integral base-frame with guide-rolls to engage the said rail, whereby the type mechanism with the rail may be fitted to either of the carriages to operate interchangeably therewith.
45. 17. A type-writing apparatus comprising a bed having a flat platen, a carriage movable in line-space direction along said platen, a second bed provided with a letter-spacing paper-carriage, and a printing mechanism mounted upon a frame which is provided with a rear hinge so that it may be swung up to expose the writing; said hinged frame being connectible to either said line-spacing carriage or said second bed.
50. 18. A type-writing apparatus comprising a bed having a flat platen, a carriage movable in line-space direction along said platen, a second bed provided with a letter-spacing paper-carriage, a printing mechanism mounted upon a frame which is provided with a hinge so that it may be swung up to expose the writing; said hinged frame being connectible to either said line-spacing carriage or said second bed; and letter-spacing mechanism mounted upon said frame and including a rack, for controlling both the movements of said frame when connected to said line-spacing carriage, and the movements of said letter-spacing carriage when said frame is connected to said second bed.
55. 19. A type-writing apparatus comprising a bed having a flat platen, a carriage movable in line-space direction along said platen, a second bed provided with a letter-spacing paper-car-

riage, a printing mechanism mounted upon a frame which is connectible to either said line-spacing carriage or said second bed; and letter-spacing mechanism mounted upon said frame and including a rack, for controlling both the movements of said frame when connected to said line-spacing carriage, and the movements of said letter-spacing carriage when said frame is connected to said second bed.

20. A type-writing apparatus comprising a bed having a flat platen, a carriage movable in line-spacing direction along said platen, a letter-spacing rack fixed upon said carriage, a printing mechanism, a frame whereon said printing mechanism is carried, said frame being connected to said carriage, and means upon said frame coöperating with said rack for feeding said frame therewith, and a second bed 15 having a letter-spacing paper-carriage; said frame being connectible to said second bed so as to be held stationary thereon, and said rack being connectible to said letter-spacing carriage so as to travel therewith and coöperate 20 with said feeding means.

21. A type-writing apparatus comprising a bed having a flat platen, a carriage movable in line-space direction along said platen, a printing mechanism, a frame whereon said printing mechanism is carried, said frame being hinged upon said carriage, a rack mounted upon said carriage, letter-spacing mechanism upon said frame to coöperate with said rack to effect letter-spacing movements of said 30 frame, the rack and letter-spacing movement being mounted so as to move with said frame as the latter turns about its hinge, and a second bed having a letter-spacing paper-carriage; said frame being connectible to said 35 second bed so as to be held stationary thereon, and said rack being connectible to said letter-spacing carriage so as to travel therewith and coöperate with said feeding means.

22. A type-writing apparatus comprising a bed having a flat platen, a carriage movable in line-space direction along said platen, a printing mechanism, a frame whereon said printing mechanism is carried, said frame being hinged upon said carriage, a rack mounted 45 upon said carriage, letter-spacing mechanism upon said frame to coöperate with said rack to effect letter-spacing movements of said frame, the rack and letter-spacing movement being mounted so as to move with said frame 50 as the latter turns about its hinge, and a second bed having a letter-spacing paper-carriage; said frame being connectible to said second bed so as to be held stationary thereon, and said rack being connectible to said letter-spacing carriage so as to travel therewith and coöperate with said feeding means, said frame 55 overlying said letter-spacing carriage but being so mounted thereon as to be capable of an upward and rearward hinge movement, to render said carriage accessible.

23. A type-writing apparatus comprising a bed having a flat platen, a carriage movable in line-spacing direction along said platen, a printing mechanism, a frame whereon said printing mechanism is carried, said frame being detachably mounted wholly upon said carriage, a second bed having a letter-spacing carriage, means whereby said frame may be connected to said second bed and supported partly upon said letter-spacing carriage, and letter-spacing devices upon said frame for controlling the letter-spacing movements of either said frame or said letter-spacing carriage.

24. A type-writing apparatus comprising a bed having a flat platen, a carriage movable in line-spacing direction along said platen, a printing mechanism, a frame whereon said printing mechanism is carried, said frame being detachably mounted wholly upon said carriage and provided with a rear hinge whereby it may be swung up and off from over said carriage and platen, a second bed having a letter-spacing carriage to which said frame may be attached so that it may swing up and off therefrom, a support upon said second bed for the front of said frame above said letter-spacing carriage, and letter-spacing devices upon said frame for controlling the letter-spacing movements of either said frame or said letter-spacing carriage.

25. A type-writing apparatus comprising a bed having a flat platen, a carriage movable in line-spacing direction along said platen, a printing mechanism, a frame whereon said printing mechanism is carried, means upon the forward portion of said carriage for supporting the front of said frame, a rod whereon the rear portion of said frame runs, said rod being detachably mounted upon said carriage and serving as a hinge-rod about which said frame may turn up, a rack upon said rod, letter-spacing mechanism upon said frame to coöperate with said rack, a second bed having a letter-spacing carriage whereon said rod may be detachably mounted, and means upon said second frame for both holding the same stationary and supporting the front portion thereof.

26. A type-writing apparatus comprising a bed having a flat platen, a carriage movable in line-spacing direction along said platen, a printing mechanism, a frame whereon said printing mechanism is carried, a rod whereby said frame is hinged in rear to said carriage, said rod being detachably mounted upon said carriage, means upon said carriage for supporting the front of said frame, a second bed having a letter-spacing carriage to which said rod is attachable, and a front support upon said second bed over said letter-spacing carriage for the front of said frame.

27. A type-writing apparatus comprising a printing mechanism, a frame upon which it is mounted, and two beds to either of which

said frame may be connected so that it may be
swung upwardly and rearwardly; said beds
being provided the first with a line-spacing
carriage and the second with a letter-spacing
carriage; and letter-spacing mechanism con-
trolling the movements of said frame when
connected to the first bed and the movements
of said letter-spacing carriage when connected
to the second bed.

In testimony whereof we have hereunto set ^{to}
our hands in the presence of two subscribing
witnesses.

JOHN JAY HANNAHS.
ANTHONY A. HIEBER.

Witnesses:

L. LEE,
A. F. HEATON.
